UNITED STATES PATENT OFFICE.

JOHN CHANDLER WOOD, OF LUMBERTON, NEW MEXICO.

AMALGAMATOR.

Application filed June 20, 1923. Serial No. 646,605.

To all whom it may concern:

Be it known that I, JOHN C. WOOD, a citizen of the United States, and a resident of Lumberton, in the county of Rio Arriba and State of New Mexico, have invented a new and Improved Amalgamator, of which the following is a full, clear, and exact description.

This invention has relation to amalgamators and is in the nature of an improvement over a prior patent granted to me on March 23, 1915, bearing United States Letters Patent No. 1,133,210.

In the prior patent above recited adjustable stops were provided whereby the flow of the mineral matter and water through the device could be regulated to agree with the various stops and settling parts of the device. It has been found, however, in actual practice that the construction and mode of adjustment were expensive and subject to disorder due to the complicated mechanism employed.

It is, therefore, the principal object of the present invention to simplify the construction and mode of adjustment in order to decrease the cost of production, allow for more accurate adjustments and at the same time facilitate the adjusting of the same.

As a still further object and advantage the invention contemplates an amalgamator in which a much larger percentage of the pulp is brought into contact with the plates.

The invention furthermore comprehends an amalgamator which is composed of a plurality of identically constructed trough sections capable of ready association with each other whereby the length of the complete amalgamating device and the number of stops and settling parts may be readily increased or decreased by the addition or removal of sections thereto.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a longitudinal sectional view

through a trough section constructed in accordance with the invention.

Fig. 2 is a fragmentary horizontal sectional view therethrough taken approximately on the line 2—2 of Fig. 1. 60

Fig. 3 is a side view illustrated the mode of associating a plurality of the trough sections.

Fig. 4 is an end view thereof.

Referring to the drawings by characters of reference, the trough sections designated generally by the reference character 10 consists of a sheet of material, preferably sheet metal, of cross sectional U-shaped construction including a bottom wall 11 and side walls 12, the said bottom wall being superimposed on a base 13 preferably consisting of a strip of wood or any other suitable material. Upon the bottom wall 11 a plate 14 is mounted which is formed with a plurality of longitudinal steps 15. Preferably the trough section which is disposed at an inclination and the plate 14 are attached to the base 13 adjacent their upper ends by screws or other fastening devices 16 which are passed therethrough and anchored in the base. The lower end of the plate 14 is curved upwardly and rearwardly to provide a substantially semi-tubular baffling member 17 which extends across the entire width of the trough with the concaved or open side facing the upper end of the trough. A substantially vertical baffle plate 18 having rearwardly and downwardly inclined steps 19 and a forwardly curved substantially semi-tubular lower end 20 is frictionally clamped and maintained between the side walls 12 by means of the transverse bolt 21, the shank of which extends through aligned openings in the side walls with the head 22 bearing against the outer side of one side wall and a thumb nut 23 threadedly engaged on the opposite end bearing against the outer side of the opposite side wall. By this arrangement 100 the vertical baffle plate 18 is free for substantially universal adjustment with respect to the U-shaped trough section and the bottom plate 14 whereby the semi-tubular end 20 thereof may be raised and lowered or advanced toward or away from the semi-tubular end 17 of the bottom plate. When the proper adjustment has been made by manipulating the baffle plate 18 by hand, the bolt 21 is manipulated to clamp the same 105

110

in place, it being understood that the side walls 12 are sufficiently yieldable to allow for their advancement toward each other. The steps 15 and 19 function to influence 5 the particles toward the bottom of the trough whereby they will be collected in the various stops and settling parts of the device. Where a plurality of trough sections 10 are associated with each other, as illustrated in Figs. 3 and 4, it will of course 10 be understood that each adjacent trough section will be of relatively different widths whereby the ends will interfit one within the other.

15 I claim:

1. In a device of the character described, a trough of substantially U-shaped cross sectional configuration, a stepped plate arranged in the bottom of said trough having an upwardly and rearwardly curved semi-circular lower end and an upright baffle plate having rearwardly and downwardly inclined steps and provided with a downwardly and forwardly curved semi-circular lower end extending into the reversely curved semi-circular lower end of the bottom plate, and means extending transversely through the side walls of the trough for clamping the same against the 20 side edges of the upright baffle plate.

2. An amalgamating trough section comprising a base strip, a substantially U-shaped member mounted on said base strip, a longitudinal stepped plate within the bot- 25

tom of said U-shaped member, an upturned rearwardly curved semi-circular lower end on said plate, a transversely disposed upright baffle plate between the side walls of the U-shaped member, said upright baffle plate having downwardly and rearwardly 40 inclined steps, and a forwardly and downwardly curved semi-circular lower end extending into the semi-circular lower end of the bottom plate and a transverse bolt extending through the side walls of the U-shaped member for clamping the same 45 against the side edges of the upright baffle plate.

3. An amalgating trough consisting of a plurality of substantially identical sections 50 of cross sectional U-shaped configuration, the ends of which sections are adapted to fit within the next adjacent lower section, a stepped plate arranged in the bottom of each section having a transversely disposed upturned rearwardly curved semi-circular lower end, a substantially vertically disposed stepped baffle plate having a reversely curved semi-circular lower end extending 55 into the semi-circular lower end of the bottom plate, and means for advancing the side walls of each U-shaped section toward each other for clamping the upright baffle plates therebetween in various relatively adjusted 60 positions with respect to each trough section 65 and bottom plate.

JOHN CHANDLER WOOD.
